UNITED STATES PATENT OFFICE.

GEORGE A. SINGERLY, OF PHILADELPHIA, PENNSYLVANIA.

DESIGN FOR A HORSESHOE.

SPECIFICATION forming part of Design No. 26,833, dated March 30, 1897.

Application filed February 10, 1897. Serial No. 622,865. Term of patent 14 years.

To all whom it may concern:

Be it known that I, GEORGE A. SINGERLY, a citizen of the United States, residing in the city and county of Philadelphia, State of Pennsylvania, have invented and produced a new and original Design for a Horseshoe, of which the following is a specification, reference being had to the accompanying drawings, forming part thereof.

The leading features of my design for a horse or animal shoe are, first, a groove in the tread of the same, extending around the toe and heel and open at the rear end of the latter, and, next, the converging or **V** shape of said groove.

Figure 1 represents a perspective view of a

horseshoe embodying my design. Fig. 2 represents a section thereof on line *x-x*, Fig. 1.

In the drawings, A designates a horseshoe, and B designates a groove in the tread thereof, the walls C of the same converging in upward direction, forming the **V** shape of the groove. The groove extends around the toe and heel and is open at the rear ends of the latter.

What I claim is—

The design for a horseshoe, substantially as described and shown.

GEORGE A. SINGERLY.
